(57) **CLAIM**

The ornamental design for a sink, as shown and described.

DESCRIPTION

In a preferred embodiment, the nature of this product is as a plumbing fixture in the form of a sink which is primarily useful for washing various items and the body parts of humans.

FIG. 1 is a left, top, front perspective view of a sink embodying my new design;

FIG. 2 is a top plan view thereof;

FIG. 3 is a front elevational view thereof, the rear elevational view thereof being a mirror image of the front shown;

FIG. 4 is a right side elevational view thereof;

FIG. 5 is a left side elevational view thereof; and,

FIG. 6 is a bottom plan view thereof.

The broken line representations in the figures are for the purpose of illustration only, and form no part of the claimed design.
